UNITED STATES PATENT OFFICE.

ISAK EKLUND, OF ST. JOSEPH, MICHIGAN, ASSIGNOR TO THE POCKET UMBRELLA COMPANY, A CORPORATION OF OHIO.

POCKET-UMBRELLA.

1,174,701.

Specification of Letters Patent.

Patented Mar. 7, 1916.

Application filed April 16, 1910. Serial No. 555,815.

To all whom it may concern:

Be it known that I, ISAK EKLUND, a subject of Sweden, residing at St. Joseph, in the county of Berrien and State of Michigan, have invented certain new and useful Improvements in Pocket-Umbrellas, of which the following is a specification.

My present invention relates to folding umbrellas of the sliding rib type, my object being to provide a novel combination of novel and improved structural details whereby to form a commercially practical device of this character.

With this in view, my invention resides in the features of construction, arrangement and operation to be hereinafter described with reference to the accompanying drawings, forming a part of this specification, and in which—

Figure 1 is a longitudinal section through my improved umbrella collapsed and in its case. Fig. 2 is a similar view thereof extended. Fig. 3 is a detail elevation, partly broken away and in section, of the tip and its parts extending into the end stick section. Fig. 4 is a detail section, on an enlarged scale, illustrating one of the section locking dogs. Fig. 5 is a similar view of the runner. Fig. 6 is a similar view, partly in elevation, showing the manner of connecting the ribs and braces, as shown in Figs. 1 and 2. Fig. 7 is a similar view showing a slightly modified form of connection. Fig. 8 is a similar view of another modified form. Fig. 9 is a perspective view of one of the members connecting the ribs and braces, and Fig. 10 is a detail sectional view on line 10—10 of Fig. 1. Fig. 11 is a detail elevation of a tip constituting a modified form over that shown in Fig. 3. Fig. 12 is a view similar to Fig. 11, with the parts extended, and Fig. 13 illustrates the two members disassociated.

The stick of my improved device comprises a handle section 5 which may have a handle 6 at its inner end, which inner end has an internal plug 7 for a purpose to be hereinafter described. Into the outer end of the handle section 5 telescopes the inner end of the intermediate section 8, into the outer end of which, in turn, telescopes the inner end of the end section 9, at the outer end of which section is rigidly affixed the nut 10 to which the inner ends of the inner rib sections 11 are secured. The stick sec-

tions are all formed of hollow tubing, preferably hexagonal in cross-section, as shown, so as to prevent the rotation of one with respect to the other, and sections 5 and 8 are provided, adjacent to their outer ends, with openings 24 adapted, when the sections are extended, to receive therethrough spring actuated dogs 12 carried by the inner ends of sections 8 and 9, respectively, whereby to prevent entire removal of sections 8 and 9 and the accidental collapsing thereof, these dogs being, however, automatically releasable when collapsing is desired, as will be shown. These dogs 12 are both alike and description of the one in the end section 9 will, therefore, suffice to cover them both. As shown in Fig. 4, this dog comprises a shank 13 pivoted at its rear end between the extensions 14 of a U-shaped member 15 inserted in the adjacent end of the stick, the fulcrum of said shank being a transverse rivet 16 extending through the stick section and thus serving also to hold member 15. The free end of shank 13 has a side shoulder 17 projecting through a slot in the stick section, and is also provided with an extension nose 18 having an inner sloping surface 19. A leaf spring 20, the outer end of which is secured between the inner surface of the stick section and an internal sleeve 21 forced in the end thereof, presses against shank 13 to force its shoulder 17 through the aperture, thus causing the dog to normally assume an angular position whereby the outer end of the said shoulder 17 extends outwardly beyond the inner end thereof. Thus when the inner end of the end section 9 is pressed within the intermediate section 8 to such an extent that the outer end of the latter abuts against the rib nut 10, forming a stop, the said inner end of the end section 9 will ride the sloping surface 19 of the extension of dog 12 of section 8 and force its head inwardly, withdrawing the inner end of the shoulder 17 beyond the slot or opening 24 of handle section 5 so that section 8 may then start its inward movement, although even when pressed inwardly, the outer edge of said shoulder would still project far enough to engage the side of the opening should section 8 be moved outwardly.

The dog 12 of the end section 9 is operated in like manner by the inner end of an internal sleeve 22 arranged within said section and provided, adjacent its inner end,

with a slot 23 through which extends a transverse rivet 23^a, projecting through the wall of section 9 to limit the sliding movement of said sleeve 22 to a very short one and one which will not affect the outer runner catch 25. This runner catch 25 comprises a shank 26 gradually enlarged toward one end and having a cut-out portion 27 in one side forming a hook 28 at its extremity, 10 and a rounded shoulder 29 adjacent to said hook. The inner end of the shank 26 is formed with a spring tail 30 intermediately coiled about a transverse rivet 26^a extending through the sleeve 22, the extremity of 15 said tail bearing against the wall of said sleeve at a point diametrically opposite to its slot 31 through which the shank 26 extends, said shank, of course, extending through a similar slot in the end section 9. 20 As seen in Fig. 3, the outer end of this sleeve 22 carries a transverse rivet 33, intermediately about which is curved one end of a rigid heavy wire 34, the opposite end 35 of which is turned back thereon in spaced relation and has its extremity 36 bent very slightly in an outward direction. This wire 34 forms a connection to the tip 37, telescopically slidable within the outer end of the 25 end section 9, and which has a transverse slit 30 adjacent to its inner end, and the material between said slit and said end, is bent inwardly to provide a catch 38 to loosely receive the bent wire end 35 which projects into said tip. Thus the tip 37 may be 30 moved the length of wire 34 independent of sleeve 22, and actuate said sleeve at the limits of such movement in relatively opposite directions. This tip 37 also has an intermediate slot 39 through which projects the inner 35 curved end 40 of a spring member 41 extending therein, the outer end of which is rigid with a plug 42 fixed in the outer end of said tip in such manner as to project slightly therebeyond. In the extended position, this spring end 40 engages the outer surface of the rib nut 10, and, being rigid with plug 42, takes the strain from the outer parts. With the sections extended, it is only necessary to manually press spring end 40 40 inwardly. The parts are then free so that tip 37 may slide in the end section until it strikes and moves the sleeve 22 inwardly to the limit of its inward movement, when its inner end will engage and force the dog 12 45 of the end section 9 inwardly to release said section and permit it to move inwardly within section 8 and release the dog 12 of the latter so it, in turn, may move inwardly in section 5 until it strikes the plug 7 of the latter, thereby rendering further inward movement impossible, and preventing strain upon the ribs and braces. 50

The same movement of the tip with relation to the inner sleeve, whereby to actuate 55 the latter at the limits of the movement of

the former only, may be readily accomplished by the somewhat different and simplified structure shown in Fig. 11 wherein is shown a tip 37^a, the inner portion of which is cut away longitudinally and reduced to 70 one-half of its normal cross-section, and which is provided with a shoulder 73^b at its inner end, the outer end of this cut-out portion resulting, of course, in a shoulder 73^c. The outer end of the sleeve, 22^a, is likewise 75 cut away and formed with inner and outer shoulders 22^b and 22^c, respectively, whereby when tip 37^a is moved toward the sleeve 22^a, the inner shoulder 22^b of the sleeve will contact, and when the tip is moved away from 80 the same, its inner shoulder 73^b will engage the outer shoulder 22^c of the sleeve. When the reduced portions of the tip and sleeve are placed to coincide, they form the same 85 cross-section and contour of either the body of the sleeve or the tip, and the end shoulders 73^b and 22^c fit within the sleeve and tip, respectively. 90

The runner comprises an inner sleeve 43 to one end of which is secured the nut 44 to 95 which the inner ends of the stretchers 45 are secured, and which has an aperture 46 adjacent to said nut, for the hook 28 of the outer runner catch 25, and a second and larger aperture 47 to accommodate the enlarged end 48 of the inner runner catch 49 secured to the handle section 5 and depressible into a slot thereof. This enlarged aperture also receives the shoulder 29 of the outer runner catch. The outer sleeve 50 of the runner, 100 which has an enlarged central portion to receive the lower runner catch, and a reduced portion to depress said catch and release the runner when said sleeve is moved upon the inner sleeve, I provide with an outstanding 105 flange 51 upon its end adjacent to the nut 44 of the inner sleeve, so that the operator's fingers cannot engage said nut 44, and for a further purpose of forming a bearing point for one end of a spring 52 coiled about the 110 inner sleeve 43 and bearing with its opposite end against the nut 44 whereby to maintain the outer sleeve in such position that the inner catch 49 cannot fail to spring out and hold the runner when the parts are being extended, this being essential in order that when the stick sections are being pulled out, the engagement of the runner by its inner catch will cause the sections of the ribs (hereafter described) to be pulled out in the 115 same operation. The outer catch prevents the umbrella blowing or turning wrong side out, and acts as a storm stop. 120

In order that the runner may be moved freely over the several dogs 12, and that 125 the operator's fingers be prevented from being scratched or cut by coming into contact with the edges of said dogs, I provide reinforcing plates 53 suitably secured upon the surface of the stick sections 5 and 8, sur- 130

rounding their openings which receive dogs 12, these plates 53 each having an integral enlargement or rib 54 upon its surface at a point where the outer edge of the dog shoulder 17 projects, the inner edge of this shoulder being flush with the surface of the plate.

As shown in Fig. 6, the outer ends of the inner rib sections 11 are provided at their outer ends with clips 55 fixed thereto and 10 which have inturned flanges 56 extending over the edges of the outer rib sections 57, slidingly disposed in said inner sections, the flanges 56 forming means to engage spring catches 58 carried by the outer rib sections 15 adjacent to their inner ends, which catches have flattened transversely projecting heads 58a upon their rear ends, for a purpose to be hereinafter described. At their inner ends, the outer rib sections 57 have members 20 59, provided with projections to fit the inner contour of said ribs and be secured therein, which projections result in depressions 60 in their outer surface for a purpose which will hereinafter appear. These members 25 59 have lateral apertured flanges 61 at their outer ends forming eyes through and to which the umbrella cover 62 is sewed, and have outwardly extending ears 63, bent inwardly and loosely about the inner rib 30 sections 11 to form guides. The members 59 have also ears 64, at their inner ends, which project in a direction opposite to that of ears 63, so as to provide means to which the end clips of the stretchers 45 are pivotally connected. The stretchers are provided, adjacent to the clips thereof, with set springs 65 formed of clock spring and bent at the outer ends to fit the inner contour of said stretchers and be secured there- 35 to, the inner ends thereof being pinched to flatten the same whereby, when the stretchers and outer rib sections are moved together, these spring ends will engage in the depressions 60 of members 59 and prevent 40 the catches 58 from being pressed to release the inner rib sections until the stretchers and outer rib sections are squeezed together, when set springs 65 will bear against said 45 catches 58. The form shown in Fig. 7 is almost identical with the form just described, with the exception of set springs 50 65a which are formed of spring wire, and in each form the depressions 60 of members 59 guide the set springs so that when pressure is applied they cannot fail to fairly 55 strike the flattened heads 58a of catches 58. The form shown in Fig. 8 differs only by a rigid member 66 in addition to set spring 65b, which is secured to the stretchers and 60 adapted to strike the catch 58 when pressure is applied. Thus, to fold the umbrella after the same has been lowered and the runner has been moved to engage its inner catch 49, it is only necessary to press spring end 65 40 inwardly, as before described, and

squeeze the ribs lightly but firmly about the stick as the tip 37 is placed against a support and pressure applied against the handle to cause the stick sections to telescope. When opening the folded umbrella, it is 70 only necessary to grasp the handle in one hand and the end of the tip 37 in the other hand, and pull them apart as far as they will go.

This construction, it may thus be seen, not 75 only provides an umbrella which is practical and unfailing in its operations of folding and unfolding, but one in which the parts are strong and lasting.

When folded, this umbrella is placed 80 within a flexible casing 67 which I preferably provide with a tab 68 at its outer end so that it may be quickly removed when use of the umbrella is desired.

I claim:

1. An umbrella of the character described, embodying a stick comprising telescopingly slidable sections, dogs carried by certain of said sections to lock the same in an extended position, said dogs comprising shanks, 90 each having a side shoulder adjacent to one end and an extension on said end provided with an inner sloping surface, U-shaped members extending into the stick sections, between the branches of which members the 95 opposite ends of said shanks are located, rivets securing said members on the sections and forming the pivots for said dogs, and springs in the sections and bearing against the said dogs.

2. An umbrella of the character described, embodying a stick comprising a plurality of telescoping sections, certain of which are provided with catches to hold them in an extended position, and certain of which have apertures to receive said catches, and reinforcing plates secured to the latter sections and surrounding their said openings said plates being enlarged at the point which is engaged by the aforesaid dogs.

3. An umbrella of the character described, embodying a stick comprising a plurality of telescoping sections, certain of which have locking dogs, to engage others of the sections, and being provided with inner sloping extensions in the path of movement of the inner end of the section telescoping therein, a sleeve within the end stick section and movable against its dog, a tip telescoping within said end section to strike and move said sleeve in one direction, and a connection between said tip and said sleeve to move the latter in the opposite direction at the limit of outward movement of the former.

4. An umbrella of the character described, embodying a stick comprising a plurality of telescoping sections, certain of which have locking dogs, to engage others of the sections, and being provided with inner

- sloping extensions in the path of movement of the inner end of the section telescoping therein, a sleeve within the end stick section, and movable against its dog, a tip telescopingly mounted within the outer portion of said end section to strike and move said sleeve in one direction, said tip having a transverse slit to adjacent its inner end, and the material beyond said slit bent inwardly 10 to form a catch, and a connecting member permanently engaging the sleeve and having a hooked end extending into said tip to engage the catch thereof when the same is moved outwardly.
- 15 5. An umbrella of the character described, embodying a stick having telescoping sections, a locking dog for said sections, said dog having an inner sloping extension located inside the section, a sleeve within the 20 section which carries the dog, said sleeve being movable against the aforesaid inner extension to retract the dog, and a tip tele-

scoping within the last-mentioned section and having means to move the sleeve inward and outward at the limits of its inward and outward movements. 25

6. An umbrella of the character described, embodying a stick having telescoping sections, a locking dog for said sections, said dog having an inner sloping extension located inside the section, a sleeve within the section which carries the dog, said sleeve being movable against the aforesaid inner extension to retract the dog, a tip telescoping within the last-mentioned section, and a 30 35 sliding connection between the tip and the sleeve.

In testimony whereof I affix my signature in presence of two witnesses.

ISAK EKLUND.
